US0D1021512S

(12) **United States Design Patent** (10) Patent No.: **US D1,021,512 S**
(45) Date of Patent: ** Apr. 9, 2024

(54) **FREESTANDING HOOD**

(71) Applicant: **WHIRLPOOL CORPORATION**,
Benton Harbor, MI (US)

(72) Inventors: **XinFeng Huang**, ShenZhen (CN);
XiaoJun Guo, Foshan (CN); **Yu Liu**,
St. Joseph, MI (US); **Kyle A. Walters**,
Kalamazoo, MI (US); **Hui Wu**,
ShenZhen (CN); **XunCai Zhang**,
DongGuan (CN)

(73) Assignee: **Whirlpool Corporation**, Benton
Harbor, MI (US)

(**) Term: **15 Years**

(21) Appl. No.: **29/748,396**

(22) Filed: **Aug. 28, 2020**

Related U.S. Application Data

(62) Division of application No. 29/642,112, filed on Mar.
27, 2018, now Pat. No. Des. 898,503.

CLAIM

We claim the ornamental design for a freestanding hood, as shown and described.

DESCRIPTION

FIG. 1 is a front top perspective view of a freestanding hood of the present disclosure;

FIG. 2 is a front bottom perspective view of the freestanding hood of FIG. 1;

FIG. 3 is a front elevational view of the freestanding hood of FIG. 1;

FIG. 4 is a rear elevational view of the freestanding hood of FIG. 1;

FIG. 5 is a first side elevational view of the freestanding hood of FIG. 1;

FIG. 6 is a second side elevational view of the freestanding hood of FIG. 1;

FIG. 7 is a top plan view of the freestanding hood of FIG. 1; and,

FIG. 8 is a bottom plan view of the freestanding hood of FIG. 1.

The broken lines depict portions of the article that form no part of the claimed design.

The broken away symbols in the drawings indicate that any portion of the article between the break lines forms no part of the claimed design.
